UNITED STATES PATENT OFFICE.

JOHN HENRY WEST, OF BAYSWATER, AND ARTHUR JAQUES, OF WATERLOO, ENGLAND.

METHOD AND APPARATUS FOR INCREASING THE YIELD OF HYDROGEN IN COAL GAS.

1,424,749.

Specification of Letters Patent. Patented Aug. 1, 1922.

Application filed May 13, 1922. Serial No. 560,806.

To all whom it may concern:

Be it known that we, JOHN HENRY WEST and ARTHUR JAQUES, both subjects of the King of Great Britain, and residing, respectively, at 33 Inverness Terrace, Bayswater, in the county of London, England, and 37 Sandringham Road, Waterloo, in the county of Lancaster, England, have invented certain new and useful Improvements in or Relating to Methods and Apparatus for Increasing the Yield of Hydrogen in Coal Gas, of which the following is a specification.

This invention relates to improved methods and apparatus for the production of hydrogen, its object being to increase the hydrogen content of gases evolved in the carbonization of coal.

In the processes for carbonizing coal generally employed a considerable proportion of the hydrogen present in the gases evolved is combined with carbon in the form of hydrocarbons, and such combined hydrogen thus reduces the amount of free hydrogen available. For the manufacture of gas for illuminating purposes there have been employed retorts constructed with both a horizontal and a vertical chamber in the former of which a fresh charge of coal was distilled for a sufficient length of time to drive off most of the volatile hydrocarbons therein which were subsequently converted into permanent inflammable gas by passing them through a more highly heated and partially carbonized mass of the same material contained in the vertical chamber. Other arrangements of apparatus for a similar purpose have comprised two vertical retorts with a conduit connecting their bottom mouth-pieces or a double retort with a centre partition having a passage therethrough so as to place in communication the two parts of the retort on each side of the partition; each retort or half of the double retort was charged alternately with the other so that the gas evolved from the fresh charge was caused to pass through the partly spent charge at a higher temperature so that more of the tars etc., were decomposed and the quality of the mixed gases maintained approximately constant. Further in the production from peat, lignite, or wood, of gas specially intended for illuminating, heating, and like purposes, it has been proposed to pass the gases produced by heating the aforementioned substances in closed retorts, to-

gether with steam or hydro-carbon vapours, through one or more retorts containing substances mainly consisting of carbon in a state of incandescence, such as the coke residue or charcoal obtained by driving off wholly or in part the volatile matters and gas of coal, peat, lignite, etc.

The present invention has for its object to obtain much higher yields of hydrogen and to effect a considerably greater decomposition of the various hydro-carbon products obtained during the carbonization of coal than has hitherto been the case, this decomposition being carried to such an extent in accordance with our improved process that not only the tarry vapours and vapours of condensable hydro-carbons are decomposed but also a high percentage of the so-called non-condensable gases such as ethylene and methane, whereby greatly increased yields of hydrogen are obtained.

According to the present invention the process for obtaining an increased proportion of free hydrogen in the gases evolved during the carbonization of coal, the said gases being intended for the production of hydrogen by extracting it therefrom, consists in passing the gases evolved during the initial stages of carbonization of the coal together with steam over partially carbonized coal or coke, the temperature of which latter has reached a value, say for example 1000° C. to 1100° C., relatively high compared with the temperatures obtaining during the initial stages of carbonization, and in effecting the carbonization at a rate sufficiently slow to allow of the decomposition of the greater proportion of all the hydro-carbon products, including the tarry vapours and even such gases as methane and ethylene, produced during the initial stages of the carbonization.

In order that the invention may be clearly understood and readily carried into effect the same will now be described more fully with reference to the accompanying drawings which illustrate the application of the present process to a battery of coke ovens, and in which Figure 1 is a view of the apparatus in elevation, Figure 2 a transverse section on an enlarged scale showing the floor and gas conduit thereunder, and Figure 3 a transverse section on the line a—a of Figure 2.

Referring to the drawings, the bank of six ovens A, B, C, D, E, F, are arranged to

work in pairs A B, C D, and E F and the individual ovens of each pair are placed in communication by means of the pipes G detachably secured to the doors K of the ovens, so that the gases from one oven can be passed through the other oven of the pair before passing into the common delivery conduit H. The pipes G are provided with steam pipes L for the purpose hereinafter referred to.

10 The operation of the apparatus is as follows:—The carbonization is conducted at a slow rate, as will be hereinafter referred to, in order to permit of a maximum of decomposition of the hydro-carbons taking place. Considering the carbonization process to be in its initial stages in the ovens B, C, and E, and in a much later stage in the ovens A, D, and F, the gases rich in hydro-carbons evolved from the former set of ovens are led off through the pipes G where they become mixed with steam introduced through the pipes L, and thereupon pass into the charge contained in the latter set of ovens in which the temperature is considerably higher than the temperature in the ovens B, C, and E. The hydro-carbons, such as methane, contained in the gases evolved from the ovens B, C, and E are decomposed during the passage of the gases through the ovens A, D and F, the decomposition being assisted by the steam which is also present and which combines with the carbon resulting from the splitting-up of the hydro-carbons and that present in the ovens A, D and F forming carbon-mon-oxide carbon-di-oxide, and hydrogen so that the gas entering the conduit G from the latter ovens contains a higher proportion of hydrogen than would otherwise be the case. When the initial stages of carbonization have been completed in the ovens B, C, and E and the proportion of hydro-carbons in the gases evolved therefrom has become relatively small, by which time the carbonization of the charges in the ovens A, D, and F will have been completed, the coke is withdrawn from the latter ovens, the pipes G are reversed to the positions indicated in dotted lines in Figure 1, and the ovens B, C and E are then ready to be utilized for the decomposition of the hydro-carbons in the gases evolved from the fresh charges introduced into the ovens A, D and F, which gases are passed together with steam into the ovens B, C, and E in which the charges are partially carbonized and now at a higher temperature than that of the ovens A, D, and F.

15 The presence of the steam prevents the deposition of the considerable amounts of carbon produced by cracking of the tars hydrocarbon vapours, etc., which have given rise to considerable difficulties in processes heretofore employed where steam has not been used.

20 The method of working described is ap-

plicable to coke ovens or horizontal or inclined gas retorts of the type which work intermittently, and of course it necessitates the ovens or retorts or groups of them commencing operation at different times. If, as in the case described the gases from the first ovens or retorts are passed together with steam directly into the second ovens or retorts, most of the tar in the gas will be decomposed and the hydrogen in it rendered available. If desired however the gases may first be passed through scrubbers and by-product plant in the usual way and only the stripped gas issuing therefrom be passed together with steam into the second oven or retort. 80

In the case of vertical gas retorts of the type which work continuously, the gas evolved in carbonization instead of being led out at the top of the retort as is the usual practice, is drawn off at the lower part, at 85 or below the zone of maximum temperature, where the carbonization process is completed and where the decomposition of the hydro-carbons with the aid of steam is effected.

The present invention is also applicable to 90 the type of horizontal or inclined retort in which one end of the retort is maintained at a high temperature relatively to the other parts of the retort and particularly to retorts of the type in which there are arrangements 95 for continually feeding the coal or coke forward.

In carrying out the present process, the carbonization is carried out at a comparatively slow rate and the duration of the initial stage of carbonization of the fuel, during which the greater part of the hydrocarbons are driven off and are conducted together with steam through a succeeding oven or retort, is equal to about one-half—say for 100 example fifteen hours—of the total coking period, and during this period the temperature gradually rises to about 900° C. 105

The hydrogen is separated from the mixture of gases in any suitable way, for example by processes such as described in the specifications of British Patents Nos. 130092, 130358 and 131,091 and the invention is obviously particularly applicable for the production of hydrogen for the synthetic manufacture of ammonia. 115

What we claim and desire to secure by Letters Patent of the United States is:

1. A process for obtaining an increased proportion of free hydrogen in the gases evolved in the carbonization of coal, the said gases being intended for the production of hydrogen by extracting it therefrom, which process consists in stripping the gases evolved during the initial stages of the carbonization of the coal by subjecting them to a purifying treatment for removal therefrom of the tarry vapours, adding steam to the stripped gases, passing the mixture of stripped gases and steam so obtained over 130

the partially carbonized coal or coke, the temperatures of which latter has reached a value relatively high compared with the temperatures obtaining during the aforesaid 5 initial stages of carbonization, and in effecting the carbonization at a rate sufficiently slow to allow the greater proportion of all the hydrocarbon products including the tarry vapours and even such gases as 10 methane and ethylene, produced during the initial stages of the carbonization, to be decomposed during their passage over the aforesaid partially carbonized coal or coke.

2. A process for obtaining an increased 15 proportion of free hydrogen in the gases evolved in the carbonization of coal, the said gases being intended for the production of hydrogen by extracting it therefrom, which process consists in adding steam to the gases 20 evolved during the initial stages of the carbonization of the coal, the said initial stages of carbonization of the coal occupying a period of time equal to about one-half of the total coking period, passing 25 the mixture of gases and steam so obtained over partially carbonized coal or coke, the temperature of which latter has reached a value relatively high compared with the temperatures obtaining during the aforesaid 30 initial stages of carbonization, and in effecting the carbonization at a rate sufficiently slow to allow the greater proportion of all the hydrocarbon products including the tarry vapours and even such gases as methane and 35 ethylene, produced during the initial stages of the carbonization, to be decomposed during their passage over the aforesaid partially carbonized coal or coke.

3. A process for obtaining an increased 40 proportion of free hydrogen in the gases evolved in the carbonization of coal, the said gases being intended for the production of hydrogen by extracting it therefrom, which process consists in adding steam to 45 the gases evolved during the initial stages of the carbonization of the coal, the said initial stages of carbonization of the coal occupying a period of time equal to about one-half of the total coking period, passing 50 the mixture of gases and steam so obtained over partially carbonized coal or coke, the temperature of which latter has reached a value of 1000° C. to 1100° C., and in effecting the carbonization at a rate sufficiently 55 slow to allow the greater proportion of all the hydrocarbon products including the tarry vapours and even such gases as methane and ethylene, produced during the initial stages of the carbonization, to be decomposed 60 during their passage over the aforesaid partially carbonized coal or coke.

4. A process for obtaining an increased proportion of free hydrogen in the gases evolved in the carbonization of coal, the said 65 gases being intended for the production of

hydrogen by extracting it therefrom, which process consists in stripping the gases evolved during the initial stages of the carbonization of the coal by subjecting them to a purifying treatment for removal therefrom 70 of the tarry vapours, the said initial stages of carbonization of the coal occupying a period of time equal to about one-half of the total coking period, adding steam to the stripped gases, passing the mixture of 75 stripped gases and steam so obtained over partially carbonized coal or coke, the temperature of which latter has reached a value relatively high compared with the temperatures obtaining during the aforesaid initial 80 stages of carbonization, and in effecting the carbonization at a rate sufficiently slow to allow the greater proportion of all the hydrocarbon products including the tarry vapours and even such gases as methane and 85 ethylene, produced during the initial stages of the carbonization, to be decomposed during their passage over the aforesaid partially carbonized coal or coke.

5. A process for obtaining an increased 90 proportion of free hydrogen in the gases evolved by the carbonization of coal in coke ovens, the said gases being intended for the production of hydrogen by extracting it therefrom, which process consists in leading 95 off the gases rich in hydrocarbons evolved from the oven or ovens in which the carbonization process is in its initial stages, adding steam to the said gases rich in hydrocarbons, passing the mixture of gases 100 and steam so obtained into a second oven or ovens in which the carbonization process is at a much later stage and where the temperature is considerably higher than in the first mentioned oven or ovens, and in effecting the carbonization at a rate sufficiently 105 slow to allow the greater proportion of all the hydrocarbon products including the tarry vapours and even such gases as methane and ethylene, evolved from the 110 oven or ovens in which the carbonization process is in its initial stages, to be decomposed during their passage through the second oven or ovens in which the carbonization process is at a much later stage.

6. A process for obtaining an increased proportion of free hydrogen in the gases evolved by the carbonization of coal in coke ovens, the said gases being intended for the production of hydrogen by extracting it 115 therefrom, which process consists in leading off the gases rich in hydrocarbons evolved from the oven or ovens in which the carbonization process is in its initial stages, stripping the said gases by subjecting them 120 to a purifying treatment for removal therefrom of the tarry vapours, adding steam to the stripped gases, passing the mixture of stripped gases and steam so obtained into a second oven or ovens in which the carboniza- 125 130

tion process is at a much later stage, and where the temperature is considerably higher than in the first mentioned oven or ovens, and in effecting the carbonization at a rate 5 sufficiently slow to allow the greater proportion of all the hydrocarbon products including the tarry vapours and even such gases as methane and ethylene, evolved from the oven or ovens in which the carbonization 10 process is in its initial stages, to be decomposed during their passage through the second oven or ovens in which the carbonization process is at a much later stage.

7. A process for obtaining an increased 15 proportion of free hydrogen in the gases evolved by the carbonization of coal in coke ovens, the said gases being intended for the production of hydrogen by extracting it therefrom, which process consists in leading 20 off the gases rich in hydrocarbons evolved from the oven or ovens in which the carbonization process is in its initial stages, stripping the said gases by subjecting them to a purifying treatment for removal there- 25 from of the tarry vapours, adding steam to the stripped gases, passing the mixture of stripped gases and steam so obtained into a second oven or ovens in which the carbonization process is at a much later stage, and 30 where the temperature has reached a value of 1000° C. to 1100° C., and in effecting the carbonization at a rate sufficiently slow to allow the greater proportion of all the hydrocarbon products including the tarry va- 35 pors and even such gases as methane and ethylene, evolved from the oven or ovens in which the carbonization process is in its initial stages, to be decomposed during their passage through the second oven or ovens in 40 which the carbonization process is at a much later stage.

8. A process for obtaining an increased proportion of free hydrogen in the gases evolved in the carbonization of coal in coke

ovens, the said gases being intended for the 45 production of hydrogen by extracting it therefrom, which process consists in leading off the gases rich in hydrocarbons evolved from the oven or ovens in which the carbonization process is in its initial stages, the said 50 initial stages of carbonization of the coal occupying a period of time equal to about one-half of the total coking period, adding steam to the said gases rich in hydrocarbons, passing the mixture of gases 55 and steam so obtained into a second oven or ovens in which the carbonization process is at a much later stage and where the temperature is considerably higher than in the first mentioned oven or ovens, 60 and in effecting the carbonization at a rate sufficiently slow to allow the greater proportion of all the hydrocarbon products including the tarry vapours and even such gases as methane and ethylene, evolved from 65 the oven or ovens in which the carbonization process is in its initial stages, to be decomposed during their passage through the second oven or ovens in which the carbonization process is at a much later stage. 70

9. Apparatus for carrying out the carbonization of coal so as to obtain an increased proportion of free hydrogen in the gases evolved by the said carbonization, comprising a series of coke ovens arranged to 75 work in pairs, a common delivery conduit for the gases evolved from the said series of ovens, pipes detachably secured to the doors of the ovens of each pair, whereby the gases from one oven can be passed through the 80 other oven of the pair before passing into the common delivery conduit, and steam pipes connected to the aforesaid detachably secured pipes for the admixture of steam with the gases passing from one oven of a pair 85 into the other oven of the pair.

JOHN HENRY WEST.
ARTHUR JAQUES.
